LEATHER BOOT

Sidney E. Cohn, Clarksville, Tenn., assignor to Acme Boot Company, Inc., Clarksville, Tenn., a corporation of Tennessee

Filed Dec. 10, 1963, Ser. No. 77,743

Term of patent 7 years

(Cl. D7—7)

I claim:

The ornamental design for a leather boot, substantially as shown.
